Attorney.

UNITED STATES PATENT OFFICE

2,452,396

GRIP ATTACHMENT FOR VIOLIN BOWS

Leopold Shopmaker, Kansas City, Kans.

Application October 15, 1945, Serial No. 622,264

6 Claims. (Cl. 84—282)

1

This invention relates to grip attachment for violin bows, and the principal object thereof is to provide a grip attachment which tends to assure proper positioning of the hand, fingers and thumb relative to the bow.

Another object is the provision of a grip attachment which functions to cause proper arching of the hand and curving or bending of the thumb.

A further object is the provision of a grip attachment having an index finger ring which insures a firm gripping and correct leading and tone production characteristics of the index finger.

A still further object of the invention is the provision of gripping means connected with the bow by means of an elastic band which holds the fingers to the bow and at the same time provides relaxation of the arm.

With these objects in view as well as other objects which will appear during the course of the specification, reference will be had to the drawing wherein—

Figure 1 is a perspective view of a grip attachment for violin bows, shown in actual use with the bow, and embodying this invention.

Fig. 2 is a perspective view showing the grip attachment and bow in another position.

Fig. 3 is an enlarged perspective view of the grip attachment detached from the bow and viewed from the front end.

Fig. 4 is a further enlarged perspective view of the device viewed from the side.

Authorities agree that there is a scientifically correct way for gripping the violin bow and that probably the most important thing the beginner needs to learn is the basically correct gripping of the bow. This grip attachment is designed for the purpose of forcing the pupil to so position his hand as to grip the bow in substantially the correct manner.

Throughout the several views like reference characters refer to like parts and the numeral 10 designates a body member preferably made of plastics, light metal or any other suitable material, and formed to present a semi-tubular hand gripping section 12 and a substantially planar section 14 disposed in tangential relation to the tubular section 12. The forward portion of planar section 14 is provided with an upturned guard 16 which is disposed at a substantially right angle to said planar section. An open finger ring 18 is pivoted at its one end by rivet 20 to guard 16 with its lower portion adjacent planar section 14 and its upper portion adjacent

2

the top of guard 16. The upper portion or the free end of the open ring 18 is provided with a hook 22 to which is attached one end of an elastic band 24 which passes around the stick 25 of bow 28. This elastic band serves to resiliently hold the front end portion of the grip attachment in proper relation to the bow stick and at the same time permits the required adjustments therebetween.

10 Referring to Figures 1 and 2 it will be noted that the operator grips the section 12 in his hand and between the inner portion of his thumb and forefinger with the index finger extended through ring 18 and against guard 16. Section 12 insures proper separation of the thumb and forefinger to insure proper arching of the thumb at the lower side of the bow stick and also provides proper relative relation of the thumb and forefinger.

15 20 It is intended that the body member extends from the front side F of the hand H to substantially the third finger so as to permit substantially free action of the third and fourth finger. The tubular portion of the body member is

25 shown as a substantially tubular form with the corner portions curved to eliminate all abrupt angles and to better fit the hand. Due to the fact that the tubular portion 12 of the body member is not closed, and is made of relatively

30 light sheet material it will flex some under the hand actions, but at the same time will function to support the hand properly, and to assume proper outward turn of the lower arm which should be approximately 45° to the upper arm.

35 The elastic band 24 is shown as a common rubber band looped about the bow stick 26 and placed over hook 22 to extend over guard 16, and downwardly to support the bow stick against

40 objectional sagging.

45 This grip attachment is intended for the use of beginners on the violin, viola, violoncello and double-bass, as a guide for the proper positioning of the hand and arm relative to the bow.

45 After the fingers have been trained to properly grip the bow the grip attachment may be dispersed with and the fingers will automatically assume the correct positions.

Many minor changes as to size and shape of 50 the parts may be made without departing from the spirit of the invention.

What I claim as new and desire to protect by

Letters Patent is:

1. A grip attachment for violin bows comprising

55 a substantially semi-circular hand gripping

member having a tangential planar section; an angled guard at the forward edge of said planar section; a resilient finger loop pivotally and adjustably mounted on the inner wall of said guard, whereby as said grip attachment is gripped by the operator with his forefinger extended through said finger loop, his thumb and fingers will be held in proper relative relation for holding the violin bow.

2. A grip attachment for violin bows comprising a substantially cylindrical hand gripping member having a tangential planar section; a finger guard disposed at the forward portion of said planar section and in angled relation thereto; a finger loop pivoted to the inner face of said guard; a hook at the upper free end of said loop; and an elastic member engaging said hook and connected to the bow stick with which the grip attachment is being used.

3. A grip attachment for violin bows comprising a substantially cylindrical hand gripping member having a tangential planar section; a finger guard at the forward edge of said planar section and disposed in angled relation thereto; a finger loop adjustably carried by said finger guard; and elastic means for connecting said finger loop to the stick of the bow on which the attachment is being used.

4. A grip attachment for violin bows comprising a substantially cylindrical hand gripping member having an upper tangential hand rest section; a guard disposed in angled relation to the front end portion of said hand rest section;

and a finger loop carried by said guard above said hand rest section and positioned below the top of said guard for receiving the forefinger of the bow operator.

5. A grip attachment for violin bows comprising a substantially cylindrical hand gripping member having an upper tangential hand rest section; a guard disposed in angled relation to the front end portion of said hand rest section; 10 a finger loop carried by said guard above said hand rest section for receiving the forefinger of the bow operator; and elastic means interconnecting said finger loop with said violin bow.

6. A grip attachment for violin bows comprising a substantially cylindrical hand gripping member of a length substantially one-half the width of the operator's hand, having an upper tangential hand rest section; a guard disposed in angled relation to the front end portion of said hand rest section; and a flexible finger loop carried by said guard above said hand rest section for receiving the forefinger of the bow operator.
